UNITED STATES PATENT OFFICE.

JOSEPH O. FORTIN, OF OTTAWA, ONTARIO, CANADA.

DRAFTING DEVICE.

Application filed October 2, 1922, Serial No. 591,850, and in Canada October 4, 1921.

This invention relates to drafting machines and more particularly to machines of the class comprising a plurality of pivotally connected parallelogram-shaped structures, one of which has one of its short links connected to an anchoring device while one short link of another structure carries a drafting appliance such as one or more rules or a protractor.

It is the object of the present invention to extend the range of usefulness of such instruments, to render them as light and as simple in construction as possible and to enable them to be folded into a small space for purposes of transport.

With these ends in view the invention consists in the arrangement and combination of parts hereinafter described and more particularly pointed out in the appended claims.

Referring now to the accompanying drawings which illustrate several convenient embodiments of the invention by way of example:—

Figure 1 is a plan view of the invention, Figure 2 is a plan view of one form of drafting appliance,

Figure 3 is a plan view of another form of drafting appliance,

Figure 4 is a sectional elevation on line 4—4, Figure 3,

Figure 5 is a fragmentary sectional elevation through the three pivotal points of the parallelogram structures on the line 5—5 of Figure 1,

Figure 6 is a sectional elevation similar to Figure 4 approximately on line 4—4 of Figure 3 but showing a modified means for connecting the drafting appliance,

Figure 7 is a fragmentary sectional elevation approximately on line 5—5 of Figure 1 but illustrating modified clamping means for the pivotal points of the parallelogram structures,

Figure 8 is a partial sectional elevation on line 8—8 of Figure 2, and

Figure 9 is a plan view showing one form of the invention as it appears for storage or transport.

The anchoring device may comprise a bar 1 which is secured as by means of screws 2 to a table or drawing board. Secured to the bar 1 is a truncated cone member 3 which is adapted to engage a conical recess in a member 4. A screw 5 passes freely through holes 55 in a short link 6 of one of the parallelogram structures and also through holes in the co-

operating cone members 3 and 4 and engages a tapped hole in the bar 1. The link 6 is rigidly connected to the member 4.

The longer parallel links 8 of the first parallelogram structure are pivoted to the ends of link 6 and to the other short link 9 by means of pins 7. The short link 9 may be supported at the same level as link 6 by means such as inverted cone shaped feet 10.

The link 9 is secured to a truncated cone 3 engaging a conical recess in a member 4 which is secured to a short link 11 of the second parallelogram structure. A screw 5 passes freely through holes in link 11, members 4 and 3 and is screwed into link 9. The

longer links 12 of the second parallelogram structure are pivotally attached to link 11 and the other short link 13 of the second parallelogram structure by means of pins 7.

The bars or links 8 and 12 are preferably provided with a series of holes spaced at equal distances apart to receive the pins 7 for the purpose of altering the distance between the parallel links 6 and 9 and between the links 11 and 13. The links 8 and 12 can at all times swing upon their pivots 7. The

links are initially adjusted to suit the position and size of the surface to be drawn upon, for example, as shown in Figure 1. The screws 5 are then screwed down to clamp link 6 in respect to bar 1 and link 9 in respect to link 11. The link 13 will then remain in the same angular position with respect to link 6 whatever the relative angular position of links 8 and 12 may be.

As the link 6 can be pivoted on the anchoring plate 1 and the link 13 in relation to the drafting member, it will be seen that should either of the parallelogram structures close up before the drafting member reaches the position desired, the drafting member may be held stationary and the closed parallelogram structure may be unclamped, opened up and reclamped, and then the movement of the drafting member may be continued and it will maintain its original angular position with regard to the work.

Secured to the under side of link 13 is a member 4 having a conical recess adapted to receive a truncated cone 18 secured to a graduated plate or ring 19 by means of screws 21 and keyed to a bushing 15 as at 22. Beneath the plate 19 is provided a bar 17 clamped in any suitable manner to the plate 19, for example, by a clamping screw 26 passing through an arcuate slot in the plate.

Secured to the under side of link 13 is a member 4 having a conical recess adapted to receive a truncated cone 18 secured to a graduated plate or ring 19 by means of screws 21 and keyed to a bushing 15 as at 22. Beneath the plate 19 is provided a bar 17 clamped in any suitable manner to the plate 19, for example, by a clamping screw 26 passing through an arcuate slot in the plate.

Secured to the under side of link 13 is a member 4 having a conical recess adapted to receive a truncated cone 18 secured to a graduated plate or ring 19 by means of screws 21 and keyed to a bushing 15 as at 22. Beneath the plate 19 is provided a bar 17 clamped in any suitable manner to the plate 19, for example, by a clamping screw 26 passing through an arcuate slot in the plate.

Secured to the under side of link 13 is a member 4 having a conical recess adapted to receive a truncated cone 18 secured to a graduated plate or ring 19 by means of screws 21 and keyed to a bushing 15 as at 22. Beneath the plate 19 is provided a bar 17 clamped in any suitable manner to the plate 19, for example, by a clamping screw 26 passing through an arcuate slot in the plate.

19 and screwed into bar 17. The bar 17 and parts carried thereby are supported as by means of three feet 24, two of which, as shown in Figures 4, 5 and 6, are carried by 5 rods 23 secured to bar 17 and locked in adjusted position by screws 25.

A vernier scale on an arc shaped plate 27 is arranged to cooperate with the graduations on plate 19, the plate 27 being secured 10 to the bar 17 by means of a screw 28. The plates 19 and 27 are marked respectively with aliquot and integral graduations. For surveyors and those who want to read to one minute of arc, the plate 19 is graduated to 15 even degrees and is indexed 0 to 180 and 180 to 360 and from 180 backwards to 90, as shown in Figs. 1 and 3. Verniers reading to one minute are graduated through 120 divisions of 59 minutes each, 60 to right and 20 60 to left of an index zero. In this case the graduated ring must have 60 unindexed 25 graduations to the right of 180 as shown in Fig. 3, for allowing a reading of $179^{\circ} 59'$. For those who want a vernier of 15 minutes, four graduations of 45 minutes each on 30 either side of the zero index, will constitute the length of the vernier, in this case the integral graduations will be carried four marks beyond 180. And for those who require even degrees only, an ordinary marker will do.

As shown in Figure 3 two rules are secured to the end of bar 17. The rules, one in line with bar 17 and one at right angles 35 thereto, are illustrated as being secured to bar 17 by means of rods 29 screwed into tapped holes in rod 17. The rods 29 rest in semi-cylindrical grooves in metal plates 31 and are secured therein by screws 30, the 40 plates 31 being secured to the rule by screws 32. The holes in the rule through which the screws 32 pass may be of larger diameter than the screws so that the rules may be adjusted about their longitudinal axes to ensure that the ruling edge is flat against the 45 drawing surface.

Figure 6 illustrates a modified means of pivotally attaching and clamping the plate 19 to the bar 17. A flange on a bolt 36 holds the plate 19 against the bar 17, the head of bolt being accommodated in a recess in a truncated cone member 34 which is attached to the plate 19, by screws 21. The link 13 of the second parallelogram structure carries a conically recessed member 4 which is adapted to be clamped in engagement with cone 34 by means of a bolt 33. In small machines the plate 19 need not be completely circular and in such cases the clamping 50 screw 26 may be located in an arcuate slot on the graduated side of the plate 19. In Figure 6 the bar 17 extends further than in Figure 4 and carries one of the rules which is attached by means of a screw 30 which 55 passes through bar 17.

In Figure 7 is shown a further form of machine which is simpler, lighter and cheaper. In this modification the female cone pieces 4 are eliminated but their functions are fulfilled by conical recesses in the 60 links 6, 11 and 13.

Figures 2 and 8 are respectively plan and partial section of an attachment suitable for use by a surveyor. In this form a plate 38 is pivotally attached to link 13 by means 65 of co-acting cone members 4 and 37 which may be clamped by a screw 5, the plate 38 being secured to cone 37 by screws 39. The plate 38 is approximately triangular and a graduated ring 40 is attached to it by means 70 of screws 41. The ring 40 is supported in horizontal position as by means of feet 42. A flange on an annular graduated plate 43 lies in a recess in the inside of plate 40 and may be clamped to plate 40 by means of a 75 nut and bolt 44, the bolt having a flange engaging the underside of ring 40 and keyed to ring 43 by a pin 45. Two elbows 46 are carried by the ring 43 and a graduated rule 48 is attached to the elbows by means of screws 80 47, engaging slots in the brackets which permits adjustment of the rule.

It will be understood that various changes may be made in the details of the construction and in the drafting attachments without departing from the scope of the invention as defined in the appended claims. For example, any number of parallelogram structures may be connected together as may be necessary to move the drafting attachment to the position where the drawing work is to be done.

What I claim is:—

1. A drafting machine comprising a plurality of pivotally connected parallelogram-shaped structures, each consisting of a pair of parallel short links pivotally connected by a pair of parallel longer links, an anchoring device, a single vertical pivot member on said anchoring device, means on said pivot member for clamping the short link at one end of the machine in any desired angular position to said device, a drafting member rotatable about the middle point of the short link adjacent the other end of the machine, and a vertical pivot member for connecting the other short link of each parallelogram structure to the adjacent short link of the other parallelogram structure.

2. A drafting machine comprising a plurality of pivotally connected parallelogram-shaped structures, each consisting of a pair of parallel short links pivotally connected by a pair of parallel longer links, an anchoring device, a single vertical pivot member on said anchoring device, means on said pivot member for clamping the short link at one end of the machine in any desired position to said device, a single vertical pivot member arranged at the middle point of the

short link adjacent the other end of the machine, a drafting member, means for clamping said drafting member on said last mentioned pivot in any desired angular position 5 in relation to the adjacent short link, a vertical pivot member for connecting the other short link of each parallelogram structure to a short link of the adjacent parallelogram structure and means on said last named 10 pivot member for clamping said pivotally connected short links to each other in any desired angular position in relation to each other.

3. A drafting machine as claimed in claim 1, comprising also a bar pivotally mounted on the short link nearest the drafting member, a graduated plate mounted on the pivot of said bar between the bar and the link, index means carried by the bar and cooperating 20 with the graduations on said plate, means for clamping the link to the plate and means for clamping the plate to the bar.

4. A drafting machine as claimed in claim 1, comprising also a bar pivotally mounted on the link nearest the drafting member, means for attaching a rule to said bar adjustably about the longitudinal axis of the rule.

5. A drafting machine as claimed in claim 1, comprising also a bar pivotally mounted

on the link nearest the drafting member, cylindrical rods carried by said bar at right angles to each other, a rule for each rod, brackets on said rules having semi-circular recesses to receive the rods and clamping 35 screws adapted to pass through holes in the rods and engage tapped holes in the rules, the holes in the rods being of larger diameter than the screws.

6. A drafting machine comprising an anchoring device, a pair of parallelogram-shaped structures each comprising four pivotally connected bars, a drafting member, a single vertical pivot member connecting the anchoring device to an end bar of one 40 of said structures, a single vertical pivot member connecting said drafting member to an end bar of the other of said structures, a single vertical pivot member connecting the remaining two end bars of said structures and clamping means associated with each of said pivot members for clamping together the said parts which are connected by said pivot members, so that said drafting member may be angularly adjusted without 45 movement of said structures, or either of said structures may be "opened" or "closed" independently of each other and of the anchoring device and drafting member.
